UNITED STATES PATENT OFFICE.

JESSIE C. CONDYLIS, OF LOUISVILLE, KENTUCKY.

DIAPER.

Application filed August 27, 1928. Serial No. 659,485.

My invention relates to diapers for infants, and has as its general object the elimination of safety pins for securing the garment about the loins of the infant.

5 The universal garment for babies, used as a diaper, is a piece of fabric which is folded and bound about the loins of the baby where it is held by a number of safety pins. The rapid growth and change in form of a baby 10 from the time it is born until it approaches the age of two years makes impractical the use of any made-up garment instead of the diaper, unless it be formed of elastic material, which material binds the legs of 15 the baby and retains undesirable heat, with the result of chafing. Moreover a made-up garment has to be very inexpensive in order that it may compete on the market with a mere square of fabric with hemmed 20 or selvage edges.

It is thus my object to provide a made-up garment, which is adjustable to fit any size of infant from birth to say two years without detachment of any part. It is my object 25 to form the garment so that it is inexpensive of manufacture.

In the usual diaper for infants, the bunching of a large portion of the fabric between the legs is uncomfortable to the infant, and 30 causes irritation. It hampers its efforts at walking, and causes an undesirable spreading of the limbs. It is likely to be harsh against the infant when soiled. The pins for attachment are usually laid within grasp 35 of the infant, when changing diapers, and are an ever present danger to it, for that reason. There is also no danger of the baby being pricked by pins.

It is thus the object of my invention to 40 do away with the bunching of fabric between the legs of the infant, and to provide a soft absorbent pad at this point. The use of pins is done away with altogether, so that this danger is absent. From the point of 45 view of washing the garment, the size thereof is so materially reduced over the usual diaper, that the washing is really easier than for the mere square of fabric used by mothers at the present time.

50 In another direction, I have provided for advantages over any garment for babies of which I have knowledge, namely: that my novel diaper is adjustable at the waist and at the hips, so that it can be fitted to the baby, snugly and yet without any binding.

These various advantages and others to be noted, I accomplish by that certain construction and arrangement of parts to be hereinafter more specifically pointed out and claimed.

60

In the drawings:

Figure 1 is a plan view of the garment, also illustrating the method of cutting it out.

Figure 2 is a perspective view showing 65 the garment at its largest size.

Figure 3 is a perspective view of the garment in its next to largest size.

Figure 4 is a plan view showing the means for shortening the diameter of the garment 70 by stitching down the buttons.

Figure 5 is a perspective view of the garment in its third size.

Figure 6 is a perspective view of the garment in its fourth size.

75

Figure 7 is a perspective view of the garment in its fifth or smallest size.

The garment is preferably formed of two thicknesses of diaper cloth, folded with a line of fold to come at the top of the garment, to give freedom for partial elasticity and surrounded otherwise by a single binding strip. This does away with any seam which would irritate the baby's back. It has a band portion and a front or flap portion. 80 Thus I have shown the garment having the band portion 1, and the flap portion 2. When folded along the fold line 4, the two ends of the original piece overlap each other, and the band portion is curved away as at 85 5, 5, at each side, and then curved out again 90 toward the end of the flap portion.

When the garment piece is folded, the buttonhole tabs 6, 6, are stitched to the ends of the band portion, and a binding 7 is 95 bound around the entire garment except at the top or fold. Binding strips as distinguished from tape are preferably used since they are not as harsh as tape and make a finer appearing garment.

The buttonhole tabs are formed with two pairs of buttonholes 8, 8, adjacent to each other nearest the top of the garment, and two single pair of buttonholes 9, at the lower end of the tabs. These pairs of holes 100 are in line with each other.

In order to provide a stout method of mounting the buttons, the flap portion has stitched to it in an angular formation, a pair of tapes 10, 10, which extend in a di- 110

vergent angle from the center of the end of the flap to about the ends of the inward curves 5 between the band and the flap. Across between the two tapes, and about 5 midway of the flap is another tape 11, which is used to secure an absorbent flannel pad 12, located on what is the inside of the garment when in use, and which has a dimension to come down between the legs 10 of the baby when the garment is in place.

The buttons are secured to the flap by means of tapes 13, which are passed through the buttons 14 and 15, and in this double formation are stitched down with the tapes 15 10. There are a pair of buttons 14 at the end of the flap and a single button lower down on the flap, for each tape 10. The buttons are thus in diverging rows. The buttonhole flaps also have the buttonholes 20 in a diverging row due to the diverging lines at 16 of the band portion of the garment. As will be noted, this arrangement gives a downward drop of the band portion of the garment in front of the abdomen 25 of the infant wearer, and is thus adapted to greatest comfort in wearing.

Stitched to the end of the flap, at the juncture point of the tapes 10, and extending beyond the end of the garment at this 30 point is a securing buttonhole flap 17, which is to be buttoned to a suitable button stitched to the band or undershirt of the baby.

The curved away sides between the band 35 and the flap form leg loops for the baby as will be evident from the perspective views.

As so constructed, the garment in its largest size is applied to the baby (see Figure 2) by folding the flap portion up before 40 between the legs, and binding the band portion about the hips and waist, and then securing the outer rows of buttonholes on the band to the taped buttons, leaving the tape free for its greatest outward extension. 45 If the baby's hips are small, the inner row of buttonholes 9 may be used. If its waist is small and hips large the inner rows of buttonholes at the top of the band may be used and the outer holes at the bottom of 50 the band used. These buttons also serve for the knee adjustment.

It may be observed how the absorbent pad passes between the legs of the baby, and how the leg loops, indicated by arrows 55 at 18, will accommodate the baby's legs.

The next smaller or second size of the garment is illustrated in Figure 3. In this case the inner buttonholes of the pairs 8 and 9 are used, and any extra fabric due 60 to adjusting the garment to a smaller compass, is in the form of the free ends of the buttonhole flaps.

In order to form the third size adjustment, the button tapes are bent inwardly 65 toward the center line of the garment as

illustrated by the arrows at 19 (Figure 4), and are stitched down by a few stitches, which can later on be picked out.

The third size of the garment is then formed as illustrated in Figure 5, wherein 70 the outer row of buttonholes on the band are united with the taped down buttons. In Figure 6 is shown the next or fourth all-over size, in which the buttonholes of the inner row on the band at each side are 75 buttoned over the taped down buttons, illustrated best in Figure 4. In this fourth size, it will usually be convenient to button the outer row of buttons on one of the buttonhole flaps over the buttons on which the 80 other buttonhole flap has been secured. This makes a further contraction of the garment at the waist, however, and can be omitted.

The fifth size of garment, which is for 85 the new born baby, is applied as follows:— The flap portion is brought between the legs and much higher up on the infant than in the other forms, so as to bring the lower buttons 15 opposite the top buttonholes 90 14 on the band. The band is then passed around the infant and buttoned with the selected pair of buttonholes 8 engaging with the two lower buttons 15 on the flap. This pinches the flap together, but the pinching 95 or folding is well up on the abdomen of the baby, so as not to form a lump between the legs. The flap where it extends up above the band, also serves as a protector for the lower chest and abdomen of the 100 infant.

I deem it of importance that the structure of the garment leaves a fold of fabric at the top or what might be termed the belt line, which fold does not require, nor does it have 105 any binding or tape thereon. This makes for a freedom of movement of the baby. The comparatively small amount of material confined between the limbs of the infant provides for comfort and the flannel pad is highly desirable from several points of view, as has been noted. The structure is economical to make, as the piece is perfectly flat. There is but one size fitting all babies with no alteration, amounting to a 110 removal of parts or taking tucks therein, and the like, the sole operation being one in which no mistake is possible, as there is but one thing to do. The usual practice will be to sell the garments with the tapes stitched 115 down to smaller adjustment position, with directions to pull the stitches, to make the size larger. The use of pins is avoided, and a well fitted diaper garment for the baby is provided.

It will be apparent that shifting about of buttons and holes, and other slight variations in shape and structure may be accomplished without departing from the spirit of my invention.

Having thus described my invention, what I claim as new and desire to secure by Letters Patent, is:—

1. A diaper garment comprising a fabric body formed with a band portion and a flap portion, said flap portion having buttons thereon in two rows lengthwise of the applied garment, and the band portion having buttonholes to engage each one row at least of said buttons, and said buttons being secured to the flap portion by means of tapes secured so as normally to permit the buttons to hang loose, and so as to permit of stitching down the tapes to bring the buttons of the rows closer to each other, and with the buttonholes on the band portion arranged in rows crosswise of the garment, and also lengthwise of the garment. 10
- 15 2. A diaper garment comprising a fabric body formed with a band portion and a flap portion, said flap portion having buttons thereon in two rows lengthwise of the applied garment, and the band portion having buttonholes to engage each one row at least of said buttons, and said buttons being secured to the flap portion by means of tapes secured so as normally to permit the buttons
- 20 3. A diaper garment comprising a fabric body formed with a waist band portion and a flap portion, with means for securing the flap and band portion in position about the limbs of an infant comprising portions having button-holes, and portions having buttons attached thereto, tapes attached to said last named portions, and said buttons being secured to the portions by said tapes, said tapes being of such length as to normally permit the buttons to hang loosely so that positions of different adjustment of buttons and button-holes may be secured by stitching the tapes so that the buttons will be supported in other than normal position. 25
